UNITED STATES PATENT OFFICE.

JOHN C. WANDS, OF ST. LOUIS, MISSOURI.

ROLLER SIDE BEARING.

SPECIFICATION forming part of Letters Patent No. 708,601, dated September 9, 1902.

Application filed November 8, 1901. Serial No. 81,585. (No model.)

To all whom it may concern:

Be it known that I, JOHN C. WANDS, a citizen of the United States, residing at the city of St. Louis, State of Missouri, have invented 5 a certain new and useful Improvement in Roller Side Bearings, of which the following is a full, clear, and exact description, such as will enable others skilled in the art to which it appertains to make and use the same, reference being had to the accompanying drawings, forming part of this specification, in which—

Figure 1 is a top plan view of my improved roller side bearing. Fig. 2 is a side elevational view, and Fig. 3 is a vertical cross-sectional view.

This invention relates to a new and useful improvement in side bearings for railway-cars, the object being to construct a device 20 of the character described in a simple and cheap manner, the device in operation affording an efficient antifriction-bearing capable of carrying the weight of the car and its load, which may be thrown upon it.

25 Prior to my present invention roller side bearings have been constructed with springs for returning the antifriction devices to a central position. These springs, however, have not been in the form of opposing 30 springs—that is, the central or normal position of the antifriction device has not been the result of equilibrium being established between the springs, but rather follows from the springs when at home being confined 35 between two stationary abutments. One of these stationary abutments when the antifriction device is shifted in either direction is lifted so as to compress the spring in advance thereof and store power in said spring 40 to restore the antifriction device to its central or normal position, when the same is released and the spring is free to act. It is evident from the above that the spring which is behind (not in advance of) the antifriction 45 device is not compressed or permitted to expand. On the contrary, it is held in a set or static condition between its stationary abutments, which condition prevails until the antifriction device is moved in the opposite direction, when the first-mentioned 50 spring will be left in a static condition, while the spring under consideration will become

the advance spring and be compressed. A construction responding to the above description is shown and described in United States Letters Patent No. 590,286, granted to me September 21, 1897.

In my present invention the springs which restore the antifriction device to its central or normal position are what I term “opposing 60 springs,” and by this I mean springs whose energies are exerted in opposite directions and whose opposing energies are exerted against the movement of the antifriction device, so as to establish a position of equilibrium with respect to said antifriction device when the same is not operatively shifted. When the antifriction device is shifted in either direction, the spring in advance of the movement thereof is compressed, while the 70 spring at the rear is permitted to expand, and to the extent of its energy the rear spring counteracts the opposition of the advance spring, so that the antifriction device can be shifted with great freedom—that is, it is 75 more sensitive to lateral movement than in the case of my former patent.

My invention consists in the construction, arrangement, and combination of the several parts, all as will hereinafter be described 80 and afterward pointed out in the claims.

In the drawings, 1 indicates a plate, preferably made of hard metal, which plate serves as a track-plate for the antifriction device.

2 indicates a guide-bracket separable from 85 the plate, said guide-bracket having an overhang 3 for coöoperating with the frame of the antifriction device.

4 indicates a guide-bracket formed with an overhang 5 and with an opening, through 90 which passes the spring guiding-rod. Both of these brackets 2 and 4 have perforated lugs or ears, through which pass the securing screws or bolts, said screws or bolts securing the bearing in position. The track-plate is 95 provided with openings, which register with the openings in the lugs or ears referred to, and in the event that holes have to be bored or drilled into the truck-bolster which is to receive my improved side bearing this track-plate serves as a templet.

6 indicates a frame formed on one side with a fin or web 7, which coöperates with the guiding-bracket 2. At the corners of the oppo-

site side are projections 8, which support a rod 9, around which are coiled expansion-springs 10, said springs bearing at their outer ends against the projections 8 on the frame 5 containing the antifriction devices and at their inner ends against the guide-bracket 4, which afford fixed abutments for said springs. Frame 6 is also provided with a guiding fin or web 11, which coöperates with the over-hang 5.

12 indicates spindles loosely journaled in the frame, upon which spindles are loosely arranged rollers 13, said rollers overlapping each other and being grouped or nested, as 15 shown. I prefer a group of rollers at each end of the frame, between which are intermediate supporting-rollers, whereby when the antifriction device is in service movement in either direction will bring all of the rollers of 20 an end group into operative position. It will be noticed that the antifriction device extends slightly beyond the track-plate at the sides, this length resulting from the fact that advantage is taken of the use of two centering-springs 25 on the rod 9, one of said springs in the event that the antifriction device is shifted being depended upon to restore the device to a central position. As the springs should not in practice be compressed to such an extent as to affect their resiliency, it follows 30 that long springs are desirable, and this length is taken advantage of to provide the two groups of rollers, one of which will be thrown out of service shortly after the commencement 35 of movement of the antifriction device, and thus the group of rollers in service will be the ones subjected to wear. In this manner the life of the bearing is considerably increased. Both springs in practice 40 are compressed before being placed in position, and consequently their energies are opposed to each other, and upon such energies becoming counterbalanced a position of equilibrium is established with respect to the roller-frame, and in this way the central or normal 45 position of the antifriction device is determined, and as the antifriction device is shifted in either direction the spring in advance thereof is compressed to a greater extent, 50 while the companion spring is permitted to expand. The said companion spring counteracts the spring under excess compression in proportion to the extent of its energy, and therefore the roller-frame and its contained antifriction 55 devices yield more readily to lateral pressure, and said roller-frame is consequently more sensitive in accommodating itself and its contained antifriction devices to the movement of the coöperating bearing member with- 60 out offering undue resistance. The spindles, upon which the rollers are loosely mounted, are preferably introduced in sockets at one side of the frame, the opposite end of the spindle being dropped into recesses in the op- 65 posite side of the frame and held in position by a plate 14.

In an application filed by me on or about

June 21, 1901, serially numbered 65,415, I have shown and described a roller side bearing in which the frame and its contained anti-friction devices coöperate with opposing springs acting to hold said parts in a central or normal position upon the establishment of equilibrium between said springs. In the other application referred to I have not, 75 broadly, claimed opposing springs coöperating with the frame and its contained anti-friction devices, as above described, reserving that right for this application.

I am aware that many minor changes in the 80 construction, arrangement, and combination of the several parts of my device can be made and substituted for those herein shown and described without in the least departing from the nature and principle of my invention. 85

Having thus described my invention, what I claim, and desire to secure by Letters Patent of the United States, is—

1. In a side bearing for cars, the combination with an antifriction device, of a rod carried thereby, and a restoring-spring arranged on said rod; substantially as described.

2. In a side bearing for cars, the combination with an antifriction device, of a rod carried thereby, a fixed guide for said rod, and a restoring-spring arranged on said rod between said fixed guide and the antifriction device; substantially as described.

3. In a side bearing for cars, the combination with an antifriction device, of a rod carried thereby, a fixed guide for said rod, and springs arranged on said rod at each side of the fixed guide; substantially as described.

4. In a side bearing for cars, the combination of an antifriction device, a frame in which the same is mounted, and opposing springs arranged at the side, and in the horizontal plane of said frame for centering the same and its carried antifriction device; substantially as described.

5. In a side bearing for cars, the combination with an antifriction device, of a guide therefor, and opposing springs arranged at the side, and in the horizontal plane of said antifriction device, for coöperating with said guide at their outer ends and with the antifriction device at their inner ends; substantially as described.

6. In a side bearing for cars, the combination with an antifriction device provided with lateral guiding-fins, of guide-brackets coöperating with said fins, and restoring-springs arranged at one side of said antifriction device; substantially as described.

7. In a side bearing for cars, the combination with an antifriction device, of laterally-extending guiding-fins, guide-brackets coöperating with said fins, and opposing springs for restoring said antifriction device, said springs being seated against one of said guiding-brackets; substantially as described.

8. In a side bearing for cars, the combination with an antifriction device, of laterally-extending guiding-fins, guide-brackets coöp-

erating with said fins, a rod carried by said antifriction device and passing through one of said guide-brackets, and springs arranged on each end of said rod and seated against said 5 guide-bracket; substantially as described.

9. In a side bearing for cars, the combination with a track-plate, of an antifriction device and separable guide-brackets therefor, said guide-brackets having integral over- 10 hangs; substantially as described.

10. In a side bearing for cars, the combination with a shiftable frame, and separated groups of antifriction devices carried by said frame; substantially as described.

15 11. In a side bearing for cars, the combination with a shiftable frame, of separated groups of antifriction devices carried at the ends of said frame, whereby when one of said groups is in service the other is partially or 20 entirely out of service, and resilient means for restoring said shiftable frame and its antifriction devices to a central position after operation; substantially as described.

12. In a side bearing for cars, the combination with a shiftable frame, of a track-plate, and separated groups of rollers in the end of the frame; substantially as described.

13. In a side bearing for cars, the combination with a track-plate, of a shiftable frame 30 carrying separated groups of rollers at its ends, one of which groups is designed to be in service while the other is wholly or partially out of service, and a centering device for said frame; substantially as described.

35 14. In a side bearing for cars, the combination with a track-plate, of a shiftable frame, spindles arranged in separated groups at the ends of said frame, and rollers loosely mounted on said spindles; substantially as de- 40 scribed.

15. In a side bearing for cars, the combination with a track-plate, of a shiftable frame, separated groups of rollers mounted in the ends of said frame, and sectional rollers over- 45 lapping each other and loosely arranged on said spindles; substantially as described.

16. In a side bearing for cars, the combination with a track-plate, of a shiftable frame, a plurality of spindles forming separated 50 groups at each end of said frame, nested or grouped rollers mounted upon said spindles, said rollers overlapping each other, and a medial spindle provided with rollers; substantially as described.

55 17. In a side bearing for cars, the combination with an antifriction device, of springs exerting their energies in opposite directions for returning the antifriction device to a central position after operation; substantially 60 as described.

18. In a side bearing for cars, the combination with a frame containing antifriction devices, of opposing springs for centering the same; substantially as described.

65 19. In a side bearing for cars, the combination with a reciprocatory antifriction device,

and opposing springs acting to center said antifriction device; substantially as described.

20. In a side bearing for cars, the combination with a reciprocatory antifriction device, and opposing springs arranged to extend parallel with the direction of movement of said antifriction devices and acting to center the same; substantially as described. 70

75 21. In a side bearing for cars, the combination with a reciprocatory antifriction device comprising a roller-carriage and a plurality of antifriction-rollers caged therein, and opposing springs arranged to center said carriage; substantially as described.

80 22. In a side bearing for cars, the combination with a reciprocatory antifriction device comprising a carriage and a plurality of roller elements caged therein to maintain definite 85 relation to the carriage, a base upon which said carriage travels, and opposing springs acting to center said carriage relatively to its length of travel across the base; substantially as described. 90

95 23. In a side bearing for cars, the combination with a frame containing antifriction devices, and opposing springs which bear at one of their ends against said frame and at their other ends against fixed abutments, whereby, the normal position of said frame is determined by the establishment of equilibrium between said springs; substantially as described.

100 24. In a side bearing for cars, the combination with a track-plate, of a frame containing antifriction devices, which frame is designed to traverse said track-plate, opposing springs, the ends of which are seated against said frame, and abutments against which the opposite ends of said springs are seated, whereby the frame is returned to a normal or central position by the establishment of equilibrium between said springs; substantially as described. 105

110 25. In a side bearing for cars, the combination with a frame containing antifriction devices, and coiled expansion-springs jointly engaging said frame in all of its positions and acting to restore said frame to a central position; substantially as described. 115

120 26. In a side bearing for cars, the combination with a frame containing antifriction devices in the form of rollers, and coiled expansion-springs under compression at all times and in all positions of said frame, said springs separately acting to restore the frame to a central position, or a position of equilibrium by the preponderating pressure of one spring over the other; substantially as described. 125

In testimony whereof I hereunto affix my signature, in the presence of two witnesses, this 6th day of November, 1901.

JOHN C. WANDS.
